H. C. REESE

AUTOMATIC POWER REGULATOR

Filed March 17, 1926

Henry C. Reese INVENTOR
Victor J. Evans

ATTORNEY

UNITED STATES PATENT OFFICE.

HENRY C. REESE, OF MOUNT PROSPECT, ILLINOIS.

AUTOMATIC POWER REGULATOR.

Application filed March 17, 1926. Serial No. 95,392.

This invention relates to certain novel improvements in automatic power regulators and has for its principal object the provision of an improved construction of this 5 character which will be highly efficient in use and economical in manufacture.

The present application constitutes an improvement over that disclosed in my former applications filed in the United 10 States Patent Office bearing Serial Numbers 678,074 and 27,275.

Among the several objects of the present invention is the production of a device of this character wherein there is provided a 15 simple combination and arrangement of parts for operation by a governor, illustrated in my former applications, for effectively controlling the throttle valve of an internal combustion engine according to the 20 load imposed upon the driving pulley of the governor.

A further object of the invention is the provision of a simple combination and arrangement of parts serving in their principal capacity to prevent sudden retroactive 25 movement of the throttle valve control member and wherein the combination and arrangement of parts will coact to permit gradual retroactive movement of the 30 throttle valve control member as the load of the driving pulley of the internal combustion engine is decreased, to close the throttle valve to permit the necessary charge of gas to the engine as is required when the engine 35 runs by reason of the decreased load.

Other objects will appear hereinafter.

The invention consists in the combination and arrangement of parts to be hereinafter described and claimed.

40 The invention will be best understood by reference to the accompanying drawings illustrating the preferred form of construction and in which:

Fig. 1 is a top plan view illustrating the 45 application of the present invention.

Fig. 2 is a fragmentary elevational view of the same taken substantially on line 2—2 of Fig. 1.

50 Fig. 3 is a fragmentary sectional detail view of the same taken substantially on line 3—3 of Fig. 1.

Fig. 4 is a fragmentary sectional detail view of the same taken substantially on line 4—4 of Fig. 1.

Fig. 5 is a fragmentary sectional view 55 taken substantially on line 5—5 of Fig. 1.

Fig. 6 is a fragmentary sectional detail view taken at a point indicated at 6—6 of Fig. 1.

In describing the preferred form of construction, as illustrated in the drawing, only 60 such parts as constitute the present invention will be indicated and for such parts as are included in the governor mechanism reference is to be had to my prior applications herein mentioned. 65

In this connection a governor is indicated at A and includes a driving pulley 10 mounted upon a shaft 11 to which is associated a slidable collar 12 at one end as indicated at 13, Fig. 1. The opposite end 70 portion 14 of the shaft 11, Fig. 1, carries a worm gear 15 adapted for meshing relation with a gear 16, as best illustrated in Fig. 2. The gear 16 is operatively carried by a shaft 17, Fig. 2, having fixed thereon for rotation therewith a worm gear 18 meshing with a gear 19 carried by and for rotation with a shaft 20. The shaft 20 is supported for rotation by a bearing block 21 in turn supported by a bracket 22, Fig. 1, carried by 80 the frame work 23 of the governor mechanism. This shaft 20 carries a ratchet wheel 24 adapted for engagement with opposite pawls 25 and 25' pivotally carried as at 26 by arms 27 mounted for free pivotal movement about the shaft 20, as illustrated in Fig. 2. The pawl 25' is normally held in engagement with the ratchet wheel 24 by reason of gravity, said pawl being provided with an enlarged extended portion 28 normally disposed to one side of the pivot 26 to normally hold this pawl 25' in engagement with the ratchet wheel. The arms 27 are operatively connected to a connecting 85 link 28^a through the medium of link members 29. This connection is accomplished through the medium of pin members 30 adapted for engagement in any one of the spaced holes 31 formed in a longitudinal direction in the connecting link 28^a. By the provision of these holes 31 it is manifest 90 that the connection between the link members 29 and the connecting link 30 can be expeditiously adjusted as required. The connecting link 28^a is connected at one end 95 indicated at 32, Fig. 2, to an operating rod 33 as at 34. The opposite end portion 35 of this operating rod works in an opening

100

105

36, Fig. 6, formed in one end portion 37' of an arm 37 of a bell crank indicated at B. This end portion of the rod is threaded as at 38 to receive nut members 39 and mounted upon this end portion, on opposite sides of the end portion of the arm 37 are equalizing springs 40 the function of which will be hereinafter set forth.

The end portion 37' of the arm 37 is detachably secured to a throttle valve operating rod 41 through the medium of spaced pin members 42 carried by this operating rod. The end portion 41' of this throttle valve operating rod has formed therein a plurality of spaced openings 42' any one of which is adapted to receive the pins 42 to permit adjustment of the end portion 37' of the arm 37 in a direction along the length of the end portion 41' of the throttle valve operating rod 41.

Referring now particularly to Fig. 1 of the drawings there is illustrated a supporting shelf 43 carried by and fixed to the frame work 23 of the governor mechanism. To this supporting shelf is pivotally connected the bell crank B which comprises the arms 37 and 45. The other arm 45 of the bell crank is operatively connected as at 46, Fig. 1, to the slidable collar 12 of the governor mechanism. This arm 45 as well as the arm 37 is pivotally connected to the supporting shelf 43 through the medium of the pintle 47. This arm 45 is fixedly secured to an extension 48 through the medium of rivets 49. This extension extends longitudinally of the end portion 51 of the arm 37 and substantially at right angles with respect to the arm 45. This extension includes upturned flanges 52, Fig. 3, having openings 53 formed therein slidably receiving bearing collars 54. These bearing collars 54 are carried by the slide rods 55 having end portions 56 operatively connected to an extension 57 formed as an integral part of the arm 37 which extension is disposed between the upturned flanges 52 as best illustrated in Fig. 3. These slide rods 55 are threaded as at 58, Fig. 3, to receive set nuts 59. The set nuts 59 and the bearing collars 54 have formed thereon collars 60 adapted to receive cushioning springs 61 mounted between the bearing collars 54 and set nuts 59 upon the slide rods 55.

The forward end portion 62 of the arm 37, Fig. 5, has secured thereto an angle member 63 having an opening 64 formed therein slidably receiving a supporting bolt 65 threaded as at 66 to receive a compression nut 67. Mounted upon this supporting bolt 65 is a compression spring 68 disposed between the compression nut 67 and a trip arm 69 adapted for engagement with an operating finger 70, illustrated in Fig. 1. This operating finger 70 is formed as an integral part of an indicating plate 71 rotatably sup-

ported by a bracket 72 carried by the supporting frame 73 secured to the supporting shelf 43. This indicating plate 71 further includes a stop arm 73' the function of which will be hereinafter set forth.

When the arm 37 is moved in the direction indicated by the arrow in Fig. 1 of the drawing the end portion 37' of the arm is adapted for engagement with an indicating finger 74 slidably working in a slot 75 formed in a plate member 76. This plate member 76 is carried by a supporting frame 73 as best illustrated in Fig. 1 of the drawings. Formed along a longitudinal edge portion 77 of the plate 76 are graduation marks 78 coacting with the indicator finger 74 to indicate the horse power of the operation of the internal combustion engine.

Having thus described the preferred form of construction of my invention I will now proceed to describe in detail the operation of the same.

From the description herein it is manifest that my invention relates primarily to the construction of the bell crank B in its operative association with the mechanism for controlling retroactive movement of the throttle valve control rod in a direction to close the throttle valve, (not shown), included as a part of the internal combustion engine with which my invention is associated. I have not described nor illustrated a throttle valve for the reason that it is apparent to those skilled in the art that any approved and known make of throttle valve can be operatively associated with the control rod 41.

The bell crank B is operable through the medium of the collar 12 which is slidably mounted for movement in opposite longitudinal directions with respect to the shaft 11, through the medium of the governor mechanism A which governor mechanism is preferably of a construction described in my co-pending applications herein mentioned.

At this time I wish to call attention to the fact that while I have indicated that the governor mechanism operates in substantially the same manner and is preferably of a construction as disclosed in my co-pending applications, it is manifest that the construction of the governor mechanism may be of any well known and approved type which includes a collar 12 movable in opposite directions longitudinally with respect to the shaft 11 for operating the bell crank B. It is, therefore, pointed out that the construction of the governor mechanism has not been illustrated in the drawing of this application nor described in the specification thereof for the reason that the governor mechanism is not included as a part of the present invention.

When this collar 12 is moved in an outward direction from the pulley 10 it acts

upon the arm 42 and urges this arm 42 to pivot about the pintle 47. When this arm 45 is urged to pivot by action of the collar 12 it acts upon the arm 37 through the medium of the spring members 61 and their associated parts to pivot the arm 37 about the pintle 47 to cause this arm 37 to act upon the operating rod 41 to move in the direction indicated by the arrow in Fig. 1 of the drawing to open the throttle valve (not shown). This movement of the collar 12 in said outward direction takes place when the load is applied to the pulley 10 to cause the pulley 10 to operate the governor mechanism A as will be clearly understood by reference to my co-pending applications.

I have found by experience that when the collar 12 is suddenly moved longitudinally of the shaft 14 in the direction indicated by the arrow in Fig. 1, that the throttle valve is suddenly closed and thereby excessively diminishes the supply of fuel to the engine whereby the engine will be either stopped or inadequately supplied with fuel for the purpose to which it is subjected. It is therefore one of the main objects of the invention to prevent this sudden closing of the throttle valve and this is accomplished through the medium of the operating rod 33 and its associated parts in the following manner.

When the control rod 41 moves in the direction indicated by the arrow in Fig. 1 the control rod 33 moves simultaneously in the same direction and urges the arms 27 carrying the pawls 25 and 25' to pivot about the shaft 20 in the direction indicated by the arrows in Fig. 2 of the drawings.

When the collar 12 is moved longitudinally of the shaft 11 in the direction indicated by the arrow in Fig. 1 of the drawing the arm 45 acts upon the arm 37 to pivot this arm 37 about the pintle 47 in an opposite direction to that herein referred to. When this arm pivots in said opposite direction it acts upon the control rod 41 to move this rod in an opposite direction to that indicated to close the throttle valve (not shown). The operating rod 33 being connected through the medium of the end portion 37' of the arm 37 to the control rod 41 for simultaneous movement prevents sudden movement of the control rod 41 in an opposite direction through the action of the bell crank B and through the medium of pawls 25 and 25' and their associated parts including the connecting link 28a. As the ratchet wheel 24 is fixed to the shaft 20 for rotation therewith it is manifest that the pawls 25 and 25' being in engagement with the peripheral edge of this ratchet wheel will permit the arms 27 to pivot about the shaft 20 in unison with the rotation of the ratchet wheel 24. It will be thus seen that the time it takes for the control rod 41 to return to the position illustrated in Fig. 1 of the drawing will de-

pend upon the speed of rotation of the shaft 20 which is operatively connected to the shaft 15 through the medium of the gear 16 and its associated parts to rotate at a less number of R. P. M. than the R. P. M. of the gear 15 and shaft 14, as best illustrated in Figs. 1 and 2 of the drawing.

During operation of the end portion 37' of the arm 37 on the control rod 41 to move this control rod in opposite longitudinal directions it will be apparent that the spring members 40 provide yieldable connection between the end portion 37' and the operating rod 33 whereby this operating rod 33 will be relieved of undue strains otherwise transmitted thereto by operation of the arm 37 of the bell crank B.

From experience I have found that it is not necessary to control the control rod 41 for slow or gradual movement in the direction indicated by the arrow in Fig. 1 for the reason that the outward movement of the collar 12 from the pulley 10 is controlled by the application of the load on the pulley 10 and when there is a sudden increase in load upon the pulley 10 I have found that the supply of fuel to the internal combustion engine must likewise be suddenly increased to supply fuel to the internal combustion engine commensurate with the application of the load upon the pulley 10.

As the arm 37 is moved in a direction to close the throttle valve (not shown) the trip finger 69 is brought into engagement with the finger 70 and rotates the indicating plate 71. On observing this indicating plate and seeing the indicating plate moved from the position originally occupied by the arm 70 as shown in Fig. 1, the operator of the machine will at once be aware of the fact that the load on the pulley 10 is greater than the engine will withstand and he thereby can govern the amount of load to be imposed upon the pulley 10. As the arm returns to the position illustrated in Fig. 1 the trip finger 69 engages the arm 73 and rotates the indicating plate 71 to its original position illustrated in Fig. 1 thereby conveying to the operator that the engine is not excessively loaded.

As this arm 37 moves in the direction indicated by the arrow in Fig. 1, the end portion 37' thereof is brought into engagement with the indicating finger 74 and moves this finger along the indicating plate 76 in the slot 74. The extreme movement of this arm will place the indicating finger at a point whereby upon observation of the graduations formed in the indicating plate 76 one can determine the amount of horse power under which the engine is operating.

From the description herein and with reference to the accompanying drawings, it is obvious that I provide a simple combination and arrangement of parts for governing the

opening and closing of a throttle valve of an internal combustion engine according to the load imposed upon the driving pulley of the engine.

5 While I have shown and described the preferred form of my invention it is to be understood that various changes and alterations may be carried out in manufacture without departing from the spirit of the invention or the scope of the appended claims.

The invention having been set forth, what I claim as new and useful is:

1. In a device of the class described, the combination with a shaft, a slidable member mounted on the shaft for movement in opposite longitudinal directions with respect to the shaft, and a throttle valve operating member, of a supporting shelf, an arm having operative connection at one end portion to the throttle valve operating member, an arm having operative connection at one end to the slidable member and extending substantially at right angles with respect to the first mentioned arms, means providing pivotal connection between the arms and the supporting shelf, and yieldable means functioning as a shock absorber for said first mentioned arm and providing operative connection between said second mentioned arm and said first mentioned arm.

2. In a device of the class described, the combination with a shaft, a member associated with the shaft for movement in opposite longitudinal directions with respect to the shaft, and a throttle valve operating member, of two arms disposed substantially at right angles with respect to each other and pivotally connected to a supporting element and defining a bell crank, one of said arms being operatively connected to the member associated with the shaft and the other arm being operatively connected to the operating member, means providing said pivotal connection between the arms and the supporting element, and means providing yieldable connections between said arms.

3. In a device of the class described, the combination with a supporting element, a shaft, a collar associated with the shaft for movement in opposite longitudinal directions with respect to the shaft, and a throttle valve operating member, of two arms disposed substantially at right angles with respect to each other defining a bell crank, one of said arms having one end portion operatively connected to the throttle valve operating member and an opposite end portion defining an extension, the other arm having an end portion operatively connected to the collar and defining at the opposite end portion an extension disposed substantially at right angles with respect to said other arm and in substantially parallel relation with respect to the extension defined by said one of the arms, means providing

yieldable connection between the extension of said one of the arms and the extension of said other arm.

4. In a device of the class described, the combination with a slidable member and a throttle valve operating rod, of rotatable means supporting the member for slidable movement, a bell crank having operative connection with the slidable member and the throttle valve operating rod adapted upon movement of the slidable member in one direction to impart movement to the throttle valve operating rod in a certain direction, a ratchet wheel, means operatively connecting the ratchet wheel to the rotatable means, and means operable upon the ratchet wheel and operatively connected to the bell crank for gradually permitting retroactive movement of the throttle valve operating rod upon operation of said slidable member in an opposite direction.

5. In a device of the class described, the combination with a slidable member and a throttle valve operating rod, of rotatable means supporting the member for slidable movement, a bell crank having operative connection with the slidable member and the throttle valve operating rod adapted upon movement of the slidable member in one direction to impart movement to the throttle valve operating rod in a certain direction, said bell crank including arms disposed substantially at right angles with respect to each other, and means yieldably connecting the arms together, a ratchet wheel, means operatively connecting the ratchet wheel to the rotatable means, and means operable upon the ratchet wheel and operatively connected to the bell crank for gradually permitting retroactive movement of the throttle valve operating rod upon operation of said slidable member in an opposite direction.

6. In a device of the class described, the combination with a slidable member and a throttle valve operating rod, an arm operatively connected to the slidable member, an extension on said arm including upturned flanges, an arm pivotally associated with the first mentioned arm and including an end portion disposed between the flanges, cushioning members carried by the flanges and operative upon the end portion of said second mentioned arm, a connection between said second mentioned arm and said throttle valve operating rod to move said operating rod in a certain direction upon movement of the slidable member in one direction, means controlling retroactive movement of the operating rod upon movement of the slidable member in an opposite direction, and means providing a connection between said controlling means and said second mentioned arm.

7. In a device of the class described, the

combination with a slidable member and a throttle valve operating rod, an arm operatively connected to the slidable member, an extension on said arm including upturned flanges, an arm pivotally associated with the first mentioned arm and including an end portion disposed between the flanges, cushioning members carried by the flanges and operative upon the end portion of said 5 second mentioned arm, a connection between said second mentioned arm and said throttle valve operating rod to move said operating rod in a certain direction upon movement of the slidable member in one direction, 10 means controlling retroactive movement of the operating rod upon movement of the slidable member in an opposite direction, and a yieldable connection between said controlling means and said second mentioned arm.

8. In a device of the class described, the combination with a slidable member, a throttle valve operating rod, an operating shaft carrying the slidable member, an arm operatively connected to the slidable member, an extension on said arm including upturned flanges, an arm pivotally associated with the first mentioned arm and including an end portion disposed between the flanges, cushioning members carried by the flanges and operative upon the end portion of said second mentioned arm, a connection between said second mentioned arm and said throttle valve operating rod to move said operating rod in a certain direction upon movement of the slidable member in one direction, 25 means controlling retroactive movement of the operating rod upon movement of the slidable member in an opposite direction, said means including a rotatable ratchet wheel carried by the operating shaft, opposite pawls adapted for engagement with the ratchet wheel, and means operatively connecting the pawls to the second 30 mentioned arm.

9. In a device of the class described, the combination with a slidable member and a throttle valve operating rod, of rotatable

means supporting the member for slidable movement, means operatively connecting the slidable member to the rod and adapted upon movement of the member in one direction to impart movement to the rod in a certain direction, and means operable upon an element of the rotatable means and having operative connection with said second mentioned means for gradually permitting retroactive movement of the rod upon operation of said slidable member in an opposite direction.

10. In a device of the class described, the combination with a slidable member and a throttle valve operating rod, of rotatable means supporting the member for slidable movement, a bell crank having operative connection with the slidable member and the rod and adapted upon movement of the slidable member in one direction to impart movement to the rod in a certain direction, and means operable upon an element of said rotatable means and operatively connected to the bell crank for gradually permitting retroactive movement of the rod upon operation of said slidable member in an opposite direction.

11. In a device of the class described, the combination with a slidable member and a throttle valve operating rod, of rotatable means supporting the member for slidable movement, means providing operative connection between the slidable member and the rod and adapted upon movement of the member in one direction to impart movement to the rod in a certain direction, a ratchet wheel, means operatively connecting the ratchet wheel to the rotatable means, and means operable upon the ratchet wheel and operatively connected to said second mentioned means for gradually permitting retroactive movement of the rod upon operation of said slidable member in an opposite direction.

In testimony whereof I affix my signature.

HENRY C. REESE.
